UNITED STATES PATENT OFFICE

2,518,473

FUEL INJECTION PUMP

Hans Hogeman, Longmeadow, and Frank S. Coe,
Springfield, Mass., assignors to American Bosch
Corporation, Springfield, Mass., a corporation
of New York

Application February 19, 1949, Serial No. 77,405

11 Claims. (Cl. 103—2)

1

This invention relates to new and improved means for supplying fuel to the cylinders of an internal combustion engine or the like and has particular reference to the provision of such a device which is relatively compact and economical in construction and efficient in operation.

An object of the invention is to provide new and improved apparatus for supplying fuel for small, high speed engines, or the like, which apparatus is relatively compact and economical in construction and efficient in operation and which makes possible the utilization of relatively inexpensive drive and mounting means.

Another object of the invention is to provide a new and improved fuel injection pump wherein in the number of components requiring exceedingly fine workmanship such as lapped fits and accurately calibrated discharge check valves have been reduced to a minimum.

Another object of the invention is to provide a device of the character described wherein it is practicable to mount the governor directly on the pump drive shaft thereby eliminating the necessity for additional gearing which is both bulky and expensive.

Another object of the invention is to provide a fuel injection pump of the single plunger type which utilizes the same delivery valve and metering means for all outlets and, therefore, provides precisely equal distribution to each of the pump outlets to the spray nozzles.

Another object of the invention is to provide a fuel device of the type set forth wherein injection takes place when the plunger is moving near maximum velocity thereby resulting in short spray duration which is desirable on certain type engines.

Another object of the invention is to provide a device of the type set forth wherein short spray durations permit the use of fixed timing through a wider speed range.

Another object of the invention is to provide a device of the type set forth which is adaptable for use with compression ignition engines or with gasoline simplified mixture control.

Another object of the invention is to provide a fuel injection pump of the type set forth wherein the time of the beginning of injection is fixed and whereby the fuel quantity to be delivered by the pump may be easily and quickly varied at will.

Another object of the invention is to provide a fuel injection pump of the single plunger type wherein a single plunger is utilized for pumping and distributing fuel to a plurality of engine

2

cylinders and which employs an adjustable sleeve control whereby the quantity of fuel delivered by the pump may be easily and quickly variable.

Other objects and advantages of the invention will be apparent from the following description taken in connection with the accompanying drawings and it will be understood that changes may be made in the details of construction and arrangement of parts shown and described, as the preferred form has been shown by way of illustration only.

Referring to the drawings:

Fig. 1 is a side view of a fuel supply apparatus embodying the invention;

15 Fig. 2 is an end view of the apparatus shown in Fig. 1;

Fig. 3 is a top or plan view thereof;

Fig. 4 is a sectional view taken on line 4—4 of Fig. 5 looking in the direction of the arrows;

20 Fig. 5 is a sectional view taken on line 5—5 of Fig. 3 looking in the direction of the arrows;

Fig. 6 is a sectional view taken on line 6—6 of Fig. 3 looking in the direction of the arrows;

Fig. 7 is a fragmentary sectional view taken on 25 line 7—7 of Fig. 2 looking in the direction of the arrows;

Fig. 8 is a fragmentary sectional view taken on line 8—8 of Fig. 3 looking in the direction of the arrows; and

30 Fig. 9 is a sectional view taken on line 9—9 of Fig. 8 looking in the direction of the arrows.

Referring more particularly to the drawings wherein similar reference characters designate corresponding parts throughout the several views, the device shown embodying the invention comprises the fuel supply pump 1, fuel injection pump 2 and governor 3 secured together to form a single relatively small, compact unit which may be mounted on or removed from the engine as a single unit.

35 The fuel supply pump 1 may be a conventional gear type supply pump or other desired form of supply pump. It will be understood that, if desired, the fuel supply pump may be formed as a separate member having a fuel supply line connected to the fuel injection pump for supplying fuel thereto instead of being mounted directly on the fuel injection pump as shown. The fuel supply pump 1 is adapted to receive fuel from

40 the fuel supply tank through a line which connects the fuel supply tank with fuel inlet 5 and fuel from the supply pump 1 passes through outlet 6 to the fuel inlet 38 for the fuel injection pump.

45 55 The fuel injection pump 2 is composed of the

pump head 7 which fits into a recess in the main pump housing 8 and is secured thereto by bolts or the like 9.

The fuel injection pump 2 is adapted to be operated by the cam 10 on camshaft 11 which camshaft is connected as for instance to four stroke cycle engines and adapted to operate at half engine speed or at engine speed, and the camshaft is, therefore, provided with a number of lobes equal to one-half the number of outlets where the pump operates at engine speed and the same number of lobes as outlets where it operates at one-half engine speed, as, for example, the pump shown has six outlets and the cam is, therefore, provided with three lobes which are adapted to reciprocate the plunger which makes two complete cycles for each rotation of the camshaft 11 and cam 10.

The camshaft 11 is mounted for rotation adjacent its opposite ends on the ball bearing 12 and the bearing 13 respectively. The mounting flange 14 is provided for securing the pump assembly in position on the engine.

On the camshaft 11 is provided the helical gear 15 which is rotated by the camshaft 11 upon rotation of the camshaft and which meshes with the helical gear 16 on the shaft 17 as hereinafter described.

The pump head 7 contains the bore 18 in which the plunger 19 is mounted for reciprocation and rotation. The bore 18 is connected by a series of outlet ports 20, each of which connects said bore 18 with its respective outlet 21, each of which is connected by a conduit or line 22 to a respective cylinder of the engine.

In the pump head 7 and aligned with the bores 18 is provided the chamber 23 in which is positioned the discharge or check valve 24 for controlling the discharge of fuel from the bore 18 and after passing through said check or discharge valve 24, said fuel passes through the supply passage 25, which for convenience in manufacture is composed of two drilled holes with the exposed end of one of said holes plugged as shown, to the annular fuel receiving groove 26 in the plunger 19 on each stroke of the plunger 19 from which it passes to the distributing groove 27 which is adapted to communicate with each of the outlets 20 in succession upon reciprocation and rotation of said plunger 19.

The plunger 19 is provided with the axial hole or passage 28 which extends from the upper end of the plunger and terminates in the spill port 29 which port communicates with the annular spill groove 30 on the plunger 19.

The pump head 7 is provided with the spill chamber 31 in which is positioned the control sleeve 32 which surrounds the plunger 19 and which is adjustable by means of the eccentric pin 33 on the rotatable shaft 34 which is connected by the pivoted lever 35 and link 36 to the governor 3 as hereinafter described.

The spill chamber 31 is connected by the passage 37 with the supply passage 38 to which is connected the supply line from the fuel supply pump 1 and from which fuel passes through the passage 39 to the bore 18. The other passage 37a is connected to port 38a which is connected to a return fuel line having a check valve therein to maintain the desired fuel supply pressure to the pump. For lubrication of the pump the passage-way 40 is provided through which some of the lubricating oil passes through the filter 41 from which it passes through the passage 42 to the lower portion of the bore 18 and also some of the

oil passes from opening 40 through passages 43 and 44 to lubricate the tappet 54 and bearing 13 respectively.

The threaded plug 46 is provided for sealing the upper end of the chamber 23 and this threaded plug 46 is removable to allow replacement of the discharge or check valve 24.

The fuel supply pump 1, which, as stated above, may be of the gear type, is adapted to be operated by the shaft 11 to which is secured the helical gear 16 which is rotated by the helical gear 15 as previously described.

The gear 47 also meshes with the gear 15 and is adapted to be rotated thereby and causes rotation of the shaft 48 on which the gear 47 is positioned which, in turn, causes rotation of the gear 49 which is fixed on the opposite end of the shaft 48 from the helical gear 47 and which meshes with gear 50 for rotating the plunger 19 as hereinafter described.

The plunger 19 has the flat sided extension 51 which is keyed with the gear 50 through the key member 52 which engages the flat side of extension 51 and keys the plunger to gear 50 for rotation through spring seat 53 which is secured to gear 50 and rotates therewith and, therefore, rotation of the gear 50 as previously described will cause simultaneous rotation of the plunger 19. The tappet 54 is provided with the roller 55 which engages the cam 10 on the camshaft 11 where, upon rotation of the camshaft 11, the lobes of the cam 10 will force the plunger 19 in a direction away from the cam 10, that is, in the direction of the pumping stroke of the plunger 19.

The end of the plunger 19 is secured to the wedge-shaped member 56 over which fits the spring seat 57. The coil springs 58 and 59 are provided for moving the plunger 19 on its return stroke and said coil springs 58 and 59 have their opposite ends engaging the spring seats 53 and 57 with the spring 58 being of smaller diameter than the spring 59 and adapted to be positioned within said spring 59.

The governor 3 is positioned within the casing 60 which is secured to the main pump housing 8 by means of the bolts 61 or other suitable means.

The governor shaft 62 is keyed to the camshaft 11 and adapted to rotate therewith.

The governor shaft 62 has a serrated portion 63 and a spider 64 is rigidly mounted upon the serrated portion 63 of the shaft 62. The spider 64 supports the governor weights 65 which are pivotally mounted thereon and each of the weights has a portion which contacts with the flange 66 on sleeve 67 through the ball bearing 68. The sleeve 67 is mounted for longitudinal movement upon the governor shaft 62 and at its opposite end from the flange 66 is provided with the flanges 69 and 70 forming seats for the springs 60 71 and 72 respectively.

A governor lever 73 is provided in the form of a yoke 74, the forks of which extend around the governor shaft 62 and each fork is pivotally mounted on the lever 75 which is pivotally mounted on the housing 60 on one side and the shaft for lever 4 on the other side. Lever 73 pivots also on flange 10. The link 36 is connected to the lever 73 at 73a.

The governor lever 73 is provided with the cam 70 76 which is adapted to engage the plate 77 which is so adjusted that the cam 76 just touches this plate 77 at full speed and full load.

The spring member 78 and adjustable surge screw 79 are provided for steadyng engine performance in case of any searching.

Lever 4 is the speed selecting lever which is connected to the governor and adjusts yoke 14 and thereby adjusts the governor spring to control the speed at which the governor weights cut off the fuel delivery by the pump.

The discharge or delivery valve 24 may be of any conventional type.

In the operation of the device the fuel supply pump 1 receives fuel through inlet line 5 and supplies fuel through outlet line 6 to inlet 38 of the fuel injection pump 2 and this fuel then passes through port 38 to bore 18, and also fills port 38a and port 38a and due to the overflow valve connected to port 38a, the desired fuel pressure is maintained in the pump. This arrangement is employed where the fuel supply pump 1 is of the gear type. Where other forms of supply pumps are employed, such as the conventional diaphragm pumps of the self pressure regulating type, the overflow valves and return line from port 38a to the fuel supply tank is not needed and, therefore, port 38a may be closed by a plug.

The supply of fuel in the passages 38 and 38a is maintained at all times and on the downward stroke of the plunger as hereinafter described, fuel enters the bore 18.

The downward or return stroke of the plunger 19 is effected by the springs 58 and 59 and the pumping stroke of the plunger is effected by the lobes of the cam 10 which engage the roller 55 on the tappet 54 and upon rotation of the cam-shaft 11, the tappet 54 is moved away from the cam-shaft and the plunger 19 which is carried thereby is, therefore, automatically moved with the tappet 54 to effect the pumping stroke of said plunger.

During the pumping stroke of the plunger 19 when the pressure of the fuel in the bore 18 is sufficient to overcome the force of the spring of the discharge or check valve 24, that valve is lifted off its seat and fuel is forced through said valve to the supply passage 25 from which it passes to the annular fuel receiving groove 26 on the periphery of the plunger 19 from which it passes to the distributing groove 27 and then to the various outlets 20 successively as said distributing groove 27 becomes aligned with each of said outlets.

Fuel in the bore 18 flows into the axial hole or passage 28 in the plunger 19 and is spilled through the spill port 29 into the spill chamber 31. The time of such spilling of fuel into the spill chamber 31 is controlled by adjustment of the sleeve 32 in a direction parallel to the axis of the plunger 19. This adjustment of the sleeve 32, therefore, also controls the quantity of fuel to be delivered through the discharge or check valve 24 before the fuel pressure in the bore 18 is relieved by spilling through the axial hole or passage 28 and spill port 29 as previously described, which spilling relieves the pressure of the fuel in the bore 18 until it is so reduced that the force of the discharge or check valve spring is sufficient to return said discharge or check valve to its seat thereby preventing the further delivery of fuel to the supply passage 25 until the next pumping stroke of the plunger 19.

The adjustment of the control sleeve 32 is automatically effected by the rotation of the rotatable shaft 34 by the pivoted lever 35 and link 36 which is connected to the governor 3 for automatic control. Rotation of the shaft 34 causes movement of the eccentric pin 33 which is connected to control sleeve 32 and, therefore, rotation of the shaft 75

34 causes a sliding movement of control sleeve 32 along the plunger 19 whereby the position of said sleeve 32 may be adjusted relative to spill groove 30 to control the spilling and thereby control the amount of fuel delivered by the pump to each of the outlets 20.

During each stroke of the plunger 19 it is rotated by means of the gear 15 on the cam-shaft 11 which rotates the gear 47 and thereby the shaft 48, circular gear 49 and circular gear 50 to thereby align the distributing groove 27 with each of the outlets 20 successively.

The pivoted lever 35 is provided with a projecting pin 86 adapted to engage and be moved by a shoulder on the spring pressed shaft 82 to shut off the pump and thereby the engine.

From the foregoing it will be seen that we have provided simple, efficient and economical means for obtaining all of the objects and advantages of the invention.

Having described our invention, we claim:

1. In a fuel injection pump, a housing, a bore in said housing, a plunger in said bore and adapted for reciprocation and rotation therein, said plunger having a pumping portion and a distributing portion, a pair of separate fuel passages, one of said passages being a delivery passage and the other a spill passage, the delivery passage extending from that portion of the bore in which fuel is pumped under pressure to the portion thereof in which fuel is distributed, a check valve in the fuel path between said pumping and distributing portions, and the spill passage being in said plunger and having a spill port, and an adjustable sleeve surrounding a portion of said plunger adjacent said spill port for controlling the spill through said port.

2. In a fuel injection pump, a housing, a bore in said housing, a plunger in said bore and adapted for reciprocation and rotation therein and serving as pumping element and distributing element, a fuel passage externally of said bore and adapted to supply fuel from the portion of said bore in which fuel is pumped under pressure to the portion thereof in which fuel is distributed, a check valve in the fuel path between said pumping and distributing portions and a spill passage in said plunger and having a spill port, and an adjustable sleeve surrounding a portion of said plunger adjacent said spill port for controlling the spill through said port.

3. In a fuel injection pump, a housing, a bore in said housing, a plunger in said bore and adapted for reciprocation and rotation therein, said plunger having a pumping portion and a distributing portion, a pair of separate fuel passages, one of said passages being a delivery passage and the other a spill passage, the delivery passage extending from that portion of the bore in which fuel is pumped under pressure to the portion thereof in which fuel is distributed, a check valve in the fuel path between said pumping and distributing portions, a spill chamber, and the spill passage being in said plunger and communicating with said spill chamber and an adjustable sleeve surrounding said plunger adjacent said spill passage and adapted to control the spill therethrough.

4. In a fuel injection pump, a housing, a bore in said housing, a plunger in said bore and adapted for reciprocation and rotation therein and serving as pumping element and distributing element, a fuel passage externally of said bore and adapted to supply fuel from the portion of said bore in which fuel is pumped under pressure to

the portion thereof in which fuel is distributed, a check valve in the fuel path between said pumping and distributing portions and a spill passage in said plunger, and an annular spill groove on said plunger communicating with said spill passage and an adjustable sleeve surrounding said plunger adjacent said spill groove and adapted to control the spill therethrough.

5. In a fuel injection pump, a housing, a bore in said housing, a plunger in said bore and adapted for reciprocation and rotation therein, said plunger having a pumping portion and a distributing portion, a pair of separate fuel passages, one of said passages being a delivery passage and the other a spill passage, the delivery passage extending from that portion of the bore in which fuel is pumped under pressure to the portion thereof in which fuel is distributed, a check valve in the fuel path between said pumping and distributing portions, the spill passage being in said plunger, and a slidable adjustable member cooperating with said spill passage for controlling the spill therethrough, a gear surrounding said plunger, a shaft, a cam on said shaft for reciprocating said plunger, a gear on said shaft, a gear meshing with said gear on said shaft and effecting rotation of said gear surrounding said plunger to thereby rotate said plunger.

6. In a device of the character described, a housing, a bore in said housing, a plunger in said bore and adapted to be reciprocated and rotated therein, said plunger having pumping and distributing portions, a fuel path externally of said bore and extending between said pumping and distributing portions, a spill chamber in said housing and communicating with said bore, and a spill passage in said plunger and adapted to allow the spilling of fuel from said bore to said spill chamber and a slidable adjustable member cooperating with said spill passage for controlling the spill therethrough.

7. In a device of the character described, a housing, a bore in said housing, a plunger in said bore and adapted to be reciprocated and rotated therein, said plunger having pumping and distributing portions, a fuel path externally of said bore and extending between said pumping and distributing portions, a spill chamber in said housing and communicating with said bore, and a spill passage and spill port in said plunger and adapted to allow the spilling of fuel from said bore to said spill chamber, and a control sleeve in said spill chamber for controlling the spilling of fuel into said chamber from said bore through said spill passage and spill port in said plunger.

8. In a device of the character described, a housing, a bore in said housing, a plunger in said bore and adapted to be reciprocated and rotated therein, said plunger having pumping and distributing portions, a fuel path externally of said bore and extending between said pumping and distributing portions, a spill chamber in said housing and communicating with said bore, and a spill passage in said plunger and adapted to allow the spilling of fuel from said bore to said spill chamber, and a control sleeve in said spill chamber for controlling the spilling of fuel into said chamber from said bore through said spill

passage in said plunger, and means whereby said sleeve may be adjusted relative to said spill passage.

9. In a device of the character described, a housing, a bore in said housing, a plunger in said bore and adapted to be reciprocated and rotated therein, said plunger having pumping and distributing portions, a fuel path externally of said bore and extending between said pumping and distributing portions, a spill chamber in said housing and communicating with said bore, and a spill passage in said plunger and adapted to allow the spilling of fuel from said bore to said spill chamber and a slidable adjustable member cooperating with said spill passage for controlling the spill therethrough, a camshaft, a cam on said shaft for reciprocating said plunger, and a gear on said shaft and adapted to effect rotation of said plunger during the reciprocation thereof.

10. In a fuel injection pump, a housing, a bore in said housing, a plunger in said bore and adapted for reciprocation and rotation therein, said plunger having a pumping portion and a distributing portion, a pair of separate fuel passages, one of said passages being a delivery passage and the other a bypass passage, the delivery passage extending from that portion of the bore in which fuel is pumped under pressure to the portion thereof in which fuel is distributed, a check valve in the fuel path between said pumping and distributing portions, a bypass chamber and the bypass passage connecting said bypass chamber and the portion of the bore in which fuel is pumped and a slidable adjustable means for controlling said bypass passage and thereby controlling the quantity of fuel delivered by the pump.

11. In a fuel injection pump, a housing, a bore in said housing, a plunger in said bore and adapted for reciprocation and rotation therein and serving as pumping element and distributing element, a fuel passage externally of said bore and adapted to supply fuel from the portion of said bore in which fuel is pumped under pressure to the portion thereof in which fuel is distributed, a check valve in the fuel path between said pumping and distributing portions and a bypass passage in said plunger and a slidably adjustable member for controlling said bypass passage and thereby controlling the quantity of fuel delivered by the pump.

HANS HOGEMAN.
